EXERCISER

Alfred J. Bruene, Chicago, Ill.

Application April 1, 1949, Serial No. 84,830

1 Claim. (Cl. 128—49)

2

This invention relates in general to an exerciser, and is more particularly concerned with a portable exerciser that is designed to exercise the legs and trunk of the person using it and is particularly characterized in employing principles of operation wherein the general form of a turntable is arranged for reciprocable action in a horizontal plane, the top surface of which is substantially flat and arranged to receive the feet of a standing person.

The subject device is a continuation in part of a mechanical exerciser disclosed in my co-pending application, Serial Number 720,121, entitled "Exerciser," now abandoned.

The contemplated exerciser is arranged so that a person standing upon the platform is guided and assisted in effecting swinging movement of the body in a hula-hula fashion with the result of awakening lazy muscles about the legs, feet and waist as the turntable reciprocates in an arcuate motion. It has been proven and noted medical authorities agree that such exercise of the waist of a person's body vitalizes muscles seldom used and hence is conducive to relieving strain, fatigue and facilitating improvement of body lines. Obviously, an exerciser as contemplated herein and employing the principles of operation of the subject device effectively conditions the abdominal muscles, stimulates the blood stream and normalizes the body functions in general.

The present improvement in exercisers is directed to simplify their construction and their mode of operation so that the simple arcuate movement of the platform is effectively controlled to provide and translate proper movement to the user's body, thereby to accomplish more advantageously the desired proper exercise of the legs and lower portions of the torso of the user. Moreover, the present device seeks to employ conventional parts wherever necessary and possible, thereby to effect reduction in the cost over the prevailing types of exercisers presently employed.

Accordingly, an object and accomplishment of the invention are to provide an exerciser, the construction and operation of which are particularly characterized as employing principles which will prolong the life and term of the operation of such exercisers.

It is a particular object and accomplishment of the invention to provide an exerciser which will furnish proper and controlled exercise for a major portion of the body in an extremely simple and efficient manner.

Another object of the invention is to provide an improved exerciser by co-relating and especially designing the various elements thereof, whereby there shall be such cooperation between said improved elements as will best serve the purpose of providing an efficient exerciser facilitating simple arcuate movements and capable of being manufactured at low cost and yet giving the maximum of satisfactory service in use.

10 A further object and accomplishment of the invention is to provide an improved exerciser designed for advantageous employment as a portable exerciser of relatively small dimension and which shall have a novel and compact arrangement of parts wherein said parts can be readily assembled and serviced.

20 A more detailed object of the invention is to provide an exerciser particularly characterized by its arrangement and design of parts to effect a controlled simple oscillating movement to the platform upon which the feet of a user is disposed, said controlled oscillating movement being accomplished by motor means mechanically operatively associated with the platform, whereby the cooperative efforts of the motor means to accomplish the oscillating movement of the platform and the swinging of the body of the user will effect a motion particularly advantageous and conducive to exercise the waist of a person's body and vitalize abdominal muscles which are seldom used, stimulate the blood stream and effectively normalize the body functions in general.

30 35 The invention seeks, as a further object and accomplishment, to provide an exerciser as contemplated herein and characterized by an arrangement of parts to more advantageously and satisfactorily perform the function required of it and adapted to provide a compact unit which will successfully combine the factors of structural simplicity and durability, and yet be economical to manufacture.

40 45 Additional objects, features and advantages of the invention disclosed herein will be apparent to persons skilled in the art after the construction and operation are understood from the within description.

50 55 It is preferred to accomplish the various objects of the invention and to practice the same in substantially the manner as hereinafter more fully described, and, as particularly pointed out in the appended claim.

With the above and other incidental objects in view, the invention has other marked improvements and superiorities which radically distin-

guish it from presently known structures, these improvements in the invention residing in the novel construction and cooperative function of the parts thereof, the combination of the parts and the arrangement thereof as illustrated in the drawing and which will be more fully described hereinafter and particularly pointed out in the claim.

In the accompanying drawing on which there is shown a preferred embodiment of the invention.

Fig. 1 is a perspective view of an exerciser embodying the features of this invention and showing the position of a person while using the device;

Fig. 2 is a top plan view of the exerciser depicted in Fig. 1;

Fig. 3 is a vertical sectional view of the exerciser depicted in Fig. 2 and illustrating the relative disposition of the parts of this invention; and

Fig. 4 is a bottom elevational view of the exerciser depicted in Figs. 2 and 3 and being taken substantially on the plane of the line 4-4 in Fig. 3.

The drawing is to be understood as being more or less of a schematic character for the purpose of illustrating and disclosing a typical or preferred form of the improvements contemplated herein and in the drawing like reference characters identify the same parts in the several views.

In the exemplary embodiment of the invention depicted in Figs. 1, 2, 3 and 4, the exerciser is designated in its entirety by the numeral 20 and comprises, in general, a base designated in its entirety by the numeral 21 and formed to define a substantially circular shape and arranged to be placed on the floor, a platform designated in its entirety by the numeral 22 and being mechanically operatively associated with and carried by said base, power transmission means designated in its entirety by the numeral 23 and comprising a motor 24, a transmission 25 carried by the base 21, and a belt drive means 26 operatively associated with the transmission 25 and portions of the base 21 and having means for connecting and transmitting power to said platform to effect controlled oscillatory movement thereof, said platform 22 having a normal position of rest and being arranged to rotate in an arc in a horizontal plane on a vertical axis between extreme positions at each side of the normal position of rest, said arrangement being particularly characterized in its mode of operation by the cooperative efforts of the power transmission means 23 and the operator to impart oscillatory movement to the platform 22.

Referring more particularly to Figs. 3 and 4, it can be seen that the base 21 is preferably formed from a suitable metal by, for example, casting or any other convenient means and the base is provided with radially disposed spokes 30 formed so that they may join integrally with the perimeter 31 of the base 21 and a centrally disposed hub 32.

It is notable that the hub 32 of the base 21 is preferably cast over a hollow preformed bearing member 33 having an axially disposed internal cylindrical sleeve bearing surface 34 and an outwardly projecting annular flange 35 at the upper end thereof. It has been found to be particularly advantageous to form the bearing member 33 of bronze. Moreover, the bearing surface 34 may be provided with grooves as indicated at 37 for the purpose of properly retaining and distributing a suitable lubricant.

The platform 22 is arranged to be limited in its rotary movement so as to provide an oscillatory action resulting from the cooperative efforts of the power transmission means 23 and the operator to impart oscillatory movement to the platform in a simple arcuate motion. Moreover, the platform 22 may also be formed, for example, by casting by any convenient conventional practice and, preferably, is cast on a preformed mating bearing member 40 which is provided with an outer cylindrical sleeve bearing surface 41 and an outwardly projecting annular flange 42 arranged to engage the corresponding parts of the hub bearing 33.

Particular attention is invited to the fact that by casting the base member 21 and the platform member 22 on their respective preformed bearing members 33 and 40, it is unnecessary to machine or otherwise finish these bearing members, and, the under face of the outwardly projecting annular flange 42 is arranged to ride upon the upward face of the outwardly projecting flange 35, thereby providing complementary horizontal and vertical bearing surfaces for rotatably supporting the platform 22 on the base 21 so that the platform may rotate in an arc in a substantially horizontal plane on a vertical axis between extreme positions at each side of a normal position of rest.

In referring to Figs. 3 and 4, it can be seen that the under side of the platform 22 is provided with an annular depending flange 45 which is arranged to operate within the outwardly extending annular wall 46 of the base 21 and is connected with the central portions thereof by means of the depending radially disposed stiffening ribs 47 of which there are eight equi-distantly and uniformly disposed about the central axis of the platform 22. The inner ends of these stiffening ribs 47 are connected integrally with the centrally cast pivot post 48 illustrated as being disposed internally of the bearing 40.

In order to retain the relative operative positions of the bearing members 33 and 40 there is provided an annular groove 49 disposed on the bearing surface 41 adjacent the lower end thereof and arranged to receive a suitable lock ring 50 having portions thereof engageable with lower portions of the bearing 33, thereby to prevent upward movement of the bearing 40 and the platform 22.

The base is provided with a bottom 52 secured to the underside of the base by means of screws 53 adapted to be received into threaded apertures (not shown) disposed on bosses 54 forming a part of the spokes 30.

Adverting to Figs. 3 and 4, it can be seen that the power transmission means 23 comprises the electric motor 24 having a suitable housing 55 arranged to be secured to the base 21 by means of suitable bolts 56. It is advantageous to employ a combination motor-transmission assembly whereby both units may be disposed in a single housing and effect a more pleasing design.

In the motor-transmission assembly as illustrated there is provided an output shaft 57 arranged to receive a pulley 58 adaptable to carry a belt 59 which is arranged to ride upon and transmit power to a pulley 60 carried for rotative movement by a pivot pin 61 carried by a spoke 70 of the base 21.

Fixedly secured to upper portions of the hub of the pulley 60 and arranged to rotate therewith is a crank arm 63 having one end thereof projecting slightly radially outwardly of the periph-

ery of the pulley 60 and provided with an aperture adaptable to receive a pivot pin 65 which interconnects a connecting link 66 with the crank arm 63. One end of the connecting link 66 is pivotally secured to a bracket 68 which is fixed to a lug 69 by any convenient means, for example, by the nut 70, said lug 69 being an integral part of a stiffening rib 47 of the platform 22.

Thus it can be seen that the drive means 26 comprising the pulleys 58 and 60, and the belt 59 arranged to ride upon said pulleys, will impart a rotating movement to the crank arm 63 which movement will cause the linkage 66 to follow and effect an oscillatory movement of the platform 22, said platform having a normal position of rest and being arranged as hereinbefore described to rotate in an arc in a horizontal plane on a vertical axis between extreme positions at each side of the normal position of rest.

In order to preload the platform and to provide proper balance to the system under certain conditions there is provided suitable spring means 75 having one end 76 thereof connected to a lug 77 forming an integral part of a stiffening rib 47 of the platform 22. The other end 78 of the spring 75 is connected to a lug 79 forming an integral part of a spoke 30 of the base 21.

Under some conditions such as, for example, when the exerciser is to be employed by a child whose weight naturally is entirely different from that of a heavy set grownup, it may be desirable to provide additional spring means (not shown) similar to that as shown at 75 but applied to and connected with a lug 80, forming an integral part of another stiffening rib 47 of the platform 22, and a lug 81 forming an integral part of another spoke 30 of the base 21.

Thus it can be seen that the exerciser may be preloaded and properly balanced by merely making a proper selection as to the spring size or by adding or subtracting the number of springs as needed.

It has been found advantageous for the purpose intended to employ a belt drive as hereinbefore disclosed; however, it is obvious that the belt drive may be replaced by a chain drive or by the employment of suitable gears. The belt drive is preferable because of its silent operation and because the resiliency of the belt provides a smoother harmonic motion. Other advantages of the belt drive will be described in detail in the operation of the device.

In order to provide a source of electric power to the motor there are provided suitable electric conduits such as, for example, the wires 85 having a suitable electric plug (not shown) disposed at one end thereof and arranged to be received into a conventional electric wall socket. Adverting to Fig. 1, it can be seen that the operator has a switch 86 in one of her hands so that she may control the starting and stopping of the device, this switch being interconnected with the motor 24 by means of the electric wires 87.

Although there is illustrated a switch and wire arrangement to be held in the hand of the user, other forms of switches may be employed such as, for example, a switch may be inserted on the upper face of the platform 22 so that when the user steps upon the platform she may step upon the switch to cause the machine to operate and when she desires the machine to be stopped her foot can be removed from the switch.

The operation of the device is as follows: Referring to Fig. 1, it can be seen that the fanciful figure of a user of the exerciser 20 is disposed upon the platform 22. When the proper position is assumed the switch 86 is turned on and by virtue of the power transmission mechanism 23 the platform will begin to oscillate in a simple arcuate motion to guide the user in controlled movements. It is important to understand that the operator cooperates with the oscillating movement of the platform 22 by swinging the body in a hula-hula fashion in a magnitude as desired. In this connection it is notable that the power transmission means 23 is so balanced that the user may oppose, to a degree, the oscillating movement of the platform, which opposition in effect places a strain on certain of the muscles of the body to effect exercise thereof. By the same token the operator can increase the magnitude of oscillating movement by following the movement of the platform and vigorously swing the body in a hula-hula fashion, thereby to effect exercise of the muscles in a different manner from that hereinbefore described. Thus by varying the technique a complete range of controlled exercise of the muscles is provided.

It is notable that the exercise and the movements resulting from the subject device is distinguishable from other types of exercising devices such as, for example, the hobby horse or the vibrating type or the type which oscillates in a vertical plane. Moreover, the result of the exercise given by the contemplated device is the awakening of lazy muscles of the legs, feet and waist as the platform 22 moves in an arcuate motion. It has been proven and noted medical authorities agree that such exercise of the waist of the person's body vitalizes muscles seldom used and hence is conducive to relieving strain, fatigue and facilitating improvement of body lines. Furthermore, the subject device effectively conditions the abdominal muscles, stimulates the blood stream and normalizes the body functions in general.

From the foregoing disclosure, it may be observed that I have provided an improved exerciser which efficiently fulfills the objects thereof as hereinbefore set forth and which provides numerous advantages which may be summarized as follows:

1. Structurally simple, efficient and durable;
2. Economical to manufacture and readily adaptable to mass production manufacturing principles; and
3. The provision of an exerciser effecting a movement of the body particularly advantageous and conducive to exercising the waist of a person's body and vitalize abdominal muscles which are seldom used and relieving strain, fatigue and facilitating improvement of body lines.

While I have illustrated a preferred embodiment of my invention, many modifications may be made without departing from the spirit of the invention and I do not wish to be limited to the precise details of construction set forth, but wish to avail myself of all changes within the scope of the appended claim.

I claim:

1. An exercising device wherein the user employs muscular inertia to oppose mechanical motive means and comprising: a base; a platform to support the user of the exercising device said platform being mounted on said base for rotation in a horizontal plane on a fixed axis in an arc be-

tween extreme positions of oscillatory movement; a motor driven speed reduction power transmission means secured to said base to transmit power to said platform to effect controlled oscillatory movement of the platform, said power transmission means including a drive shaft, a first pulley mounted on said shaft, a second pulley carried by said base, and a belt arranged to ride on said pulleys to facilitate rotation of said second pulley responsive to operation of said motor driven speed reduction means, a crank arm fixedly secured to said second pulley for rotation therewith and having one end thereof projecting radially outwardly of the periphery of said second pulley, and a connecting link one end of which is pivotally connected to the projecting end of said crank arm and the other end of which is pivotally connected to said platform; and spring means attached between the base and the platform and being ineffective during arcuate movement of the platform midway of the extreme positions of oscillatory but becoming effective during the arcuate movement of the platform in the zone at each side of the midway position to the extreme positions of oscillatory movement to offer a variable force to op-

5 pose relative movement between the base and platform, the change of direction of movement of the platform at the extreme positions of oscillatory movement being opposed by muscular inertia exerted by the user, and said variable force of said spring means cooperating with the power and action of said motor driven speed reduction power transmission means being effective to overcome the muscular inertia exerted by the user.

10

ALFRED J. BRUENE.
